UNITED STATES PATENT OFFICE.

LAURENCE P. PALMER, OF UNIONTOWN, PENNSYLVANIA.

COKE-OVEN.

992,684.

Specification of Letters Patent. Patented May 16, 1911.

Application filed February 11, 1911. Serial No. 607,976.

To all whom it may concern:

Be it known that I, LAURENCE P. PALMER, a resident of Uniontown, in the county of Fayette and State of Pennsylvania, have invented certain new and useful Improvements in Coke-Ovens, of which the following is a specification.

The object of this invention is to provide a bee-hive coke oven of such form that all parts thereof immediately above the floor are accessible to the fork or rake of a coke drawing machine or hand scraper for completely emptying the oven.

As heretofore constructed, the door jambs of these ovens are curved in their inner surfaces at and above the plane of the floor so that it is impossible to extend a straight line through any part of the oven door from any point on its side wall without pocketing more or less of the oven space. The rake or fork of a mechanical coke drawer cannot operate in space thus pocketed, as will be understood, with the result that such machines are not available for completely emptying the oven and must unnecessarily be shifted from side to side of the oven door, the remainder being removed later by hand, or permitted to remain and be wasted. The effort to remove this pocketed coke frequently results in damage to the curved jambs, and in the case of hand-drawn ovens the conditions are practically the same.

With an oven of the design contemplated by the present invention, all portions immediately above the floor are accessible to the mechanical or hand drawer for removing all the coke with the least amount of labor and the minimum shifting of the mechanical coke drawer or hand scraper.

In the accompanying drawings, Figure 1 is a vertical cross-section of a bee-hive oven constructed in accordance with the invention, and Fig. 2 is an elevation of a portion thereof illustrating the door opening, the outer door frame being removed. Fig. 3 is a sectional plan of a portion of the oven taken through the door opening, the plane of section of the lefthand door jamb being indicated by line *a—a*; Fig. 2, and the plane of section of the righthand jamb being indicated by line *b—b*. Figs. 1 and 2. Fig. 4 is an edge view of one of the jambs, looking in the direction of arrow A, Fig. 3.

Referring to the drawings, 2 designates the floor, and 3 the portions of a curved side wall rising from the floor and merging into

the wall parts which form the jambs for door opening 4, these jambs supporting the door arch 5. Cast-iron frame 4 is usually fitted to the outer faces of the jambs. Each of the jambs may be formed of several blocks superposed one upon the other. In the present adaptation, the blocks are three-high, 6 designating the lowermost blocks, 7 the intermediate blocks, and 8 the uppermost blocks. It will be understood, however, that the number may vary. In the present adaptation, in addition to being three-high there are two courses of these blocks, the inner course 9 being intermediate the wall parts 3 and the outer course 10. It will be understood, however, that the number of courses may vary.

Blocks 6 are formed with flat inner faces 11, so that upwardly from floor 2 a distance 75 corresponding to the height of blocks 6, a straight line may be extended inwardly through any part of the door opening 4 and along said faces 11 and intersect wall 3 without crossing or pocketing any of the oven space. From this it will be understood that the rake or fork of a coke drawing machine or a hand scraper, operating through door opening 4, may quickly and readily gain access to all portions of the oven floor, no part being pocketed and inaccessible and without being required to repeatedly shift the position of the mechanical drawer or hand scraper. As the drawing scraper or other tool operates on the bottom of the oven, it is sufficient if all parts immediately above the floor can be reached.

The second tier 7 of the jamb blocks are curved on their inner surfaces as indicated at 12, such curvature increasing vertically 95 and being continued and forming a continuation of the similar, though increasing, curvature 13 of the uppermost blocks 8, the latter being of sufficient size or area to support the door arch 5.

While the invention is designed primarily for ovens of bee-hive type, and is so illustrated, it may be employed in any oven having curved walls adjacent to the door opening.

I claim:

1. A coke oven having a bottom, and horizontally curved side walls provided with an entrance, door jambs at the oven entrance forming continuations of the inner side of the side walls, the lower portion of the inner surface of the jambs being a vertical plane

2
and arranged so that a straight line may be drawn from and through any part of the oven door to any point on the meeting line of the bottom and inner surface of the oven side walls.

2. A coke oven having a bottom, and horizontally curved side walls provided with an entrance, door jambs at the oven entrance forming continuations of the inner side of the side walls, the lower portion of the inner surface of the jambs being a vertical plane a distance upwardly from the oven bottom so that a straight line may be drawn from and through any part of the oven door to any point on the meeting line of the bottom and inner surface of the oven side walls, and the inner surfaces of the upper portions of the jambs being curved.

3. A bee-hive coke oven having a bottom, and horizontally curved side walls provided with a door opening extending upwardly from the oven floor, door jambs at opposite

sides of the opening and forming continuations of the inner side of the side walls of the oven, the lower portion of the inside of the jambs being a vertical plane so that a straight line may be extended inwardly from any point of the door opening to any point of the meeting line of the bottom and inner side of the curved side walls of the oven without pocketing any of the oven space, the inner surfaces of the upper portions of the jambs being in part curved correspondingly to the curvature of the oven walls and in part shaped to conform with the door opening, and an arch for the door opening supported by the said upper portions of the jambs.

In testimony whereof I affix my signature in presence of two witnesses.

LAURENCE P. PALMER.
